UNITED STATES PATENT OFFICE.

LEWIS U. BEAN, OF PHILADELPHIA, PENNSYLVANIA.

STAND FOR INKS, COLORS, LIQUIDS, &c.

SPECIFICATION forming part of Letters Patent No. 651,156, dated June 5, 1900.

Application filed January 16, 1899. Serial No. 702,383. (No model.)

To all whom it may concern:

Be it known that I, LEWIS U. BEAN, a citizen of the United States, residing in the city and county of Philadelphia, State of Pennsylvania, have invented a new and useful Improvement in Stands for Inks, Colors, Liquids, &c., which improvement is fully set forth in the following specification and accompanying drawings.

10 My invention consists of a stand having a platform therein adapted as a stop for the depth of dipping of a pen, brush, or other instrument into the stand to limit the fluid taken up by the same and prevent dropping, 15 &c., said plate being carried by a stem which admits of adjustment to the desired extent, the stem being frictionally engaged by guides, whereby it retains its adjustment.

Figure 1 represents a side elevation of a 20 stand embodying my invention. Fig. 2 represents a top or plan view thereof. Fig. 3 represents a vertical section on line xx , Fig. 2.

Similar letters of reference indicate corresponding parts in the figures.

25 Referring to the drawings, A designates a vessel or body of the order of an inkstand, and B designates a hinged cover on the screw-cap C thereof for closing the supply opening and inlet D of and to said vessel. Rising 30 from said cap C are uprights or pieces forming a guide E for the stem F, which is fitted between said pieces and passed through the opening G in the cap, its lower ends having connected with it the platform H, which by 35 means of said stem may be raised and lowered in the vessel, and consequently in the fluid, such as ink, therein, the lower portions of said guide serving to cause the stem to move true in its up and down motions and avoiding 40 turning of said stem, and consequently

of the platform. By this provision the depth that a pen, brush, &c., is to enter the vessel may be regulated by raising or lowering the platform, so that said pen, &c., may dip into and be supplied by the fluid to the required extent and dropping of fluid is prevented. Again, when the fluid becomes low the platform may be depressed, so as to displace some of the fluid and raise it above said platform.

The upper portions E' of the guide E are somewhat elastic in their nature, so that they may press firmly against the portion of the stem between the same and by the resultant friction retain the platform at the set position. The upper ends E² of said pieces E are flaring, so that they may be engaged by the thumb or fingers to force the pieces together or spread them apart to adjust their pressure on the stem.

Having thus described my invention, what I claim as new, and desire to secure by Letters Patent, is—

1. A vessel provided with a cover and an inlet, a guide rising from said cover, a vertically-movable stem in said guide, and a platform within the vessel carried by said stem, said guide being resilient and bearing against said stem on opposite sides by elastic pressure.

2. A vessel provided with a cover and an inlet, a guide rising from said cover, a vertically-movable stem passing through said guide and cover into the vessel, and a platform within the vessel carried by said stem, said guide being resilient and bearing against said stem and having flaring upper ends.

LEWIS U. BEAN.
